UNITED STATES PATENT OFFICE.

SAMUEL M. BLOCH, OF CLEVELAND, OHIO, ASSIGNOR TO THE BLOCH COMPANY, OF CLEVELAND, OHIO, A CORPORATION OF OHIO.

CONDUCTOR'S VEST.

1,407,459.

Specification of Letters Patent. Patented Feb. 21, 1922.

Application filed August 2, 1919. Serial No. 314,273.

To all whom it may concern:

Be it known that I, SAMUEL M. BLOCH, a citizen of the United States, and a resident of Cleveland, county of Cuyahoga, and State 5 of Ohio, have invented a new and useful Improvement in Conductors' Vests, of which the following is a specification, the principle of the invention being herein explained and the best mode in which I have contemplated 10 applying that principle, so as to distinguish it from other inventions.

The present invention, relating, as indicated, to conductors' vests, is directed to a particular type of garment generally known 15 by the above title, and sometimes called a vestlette, which may be worn by conductors under the coat to carry coins, tickets, report sheets, transfers and the like for the purpose of saving the coat or ordinary vest. 20 The purpose of the present invention is the provision of an improved type of vestlette of greater convenience than those heretofore in use and of an improved and less expensive construction. To the accomplishment 25 of the foregoing and related ends, said invention, then, consists of the means herein- after fully described and particularly pointed out in the claim.

The annexed drawing and following description set forth in detail certain mechanism embodying the invention, such disclosed means constituting, however, but one of various mechanical forms in which the principle of the invention may be used.

35 In said annexed drawing:—

Fig. 1 is a front view of my improved vestlette; Fig. 2 is a partial rear view of the same; and Fig. 3 is an enlarged transverse section illustrating the construction of 40 the material for the garment.

In Figs. 1 and 2, this garment will be seen to consist of a main body portion 1 equivalent in its contour and size to the front parts of an ordinary vest, but unprovided with 45 any opening or buttons down the front. This main portion is provided with two upwardly extending parts 2, to which are attached straps 3, adapted to be crossed behind the back of the wearer and fastened to 50 the buttons which are attached at 4. An adjustable belt or strap 5 is also provided for attachment to the buttons 6 on the lower portion of the vest.

The use to which these garments are subjected is extremely severe, as the pockets

with which they are provided are always more or less filled with heavy articles, such as small coins, so that the weight on the fabric of the garment is very considerable. In addition to this the pockets are used very 60 much, the conductor having to insert his hand in his pockets at frequent intervals, thus causing stretching of the cloth and wearing of the same along the edges, and difficulty has been experienced in finding a 65 material which will resist this extremely hard service and at the same time not be too expensive for the purpose. I have overcome this difficulty by the use of a combination of two fabrics which are shown in Fig. 3. The 70 first of these fabrics is the lining 7, which is of a heavy canvas or similar material, upon which is superimposed a similarly shaped strip of cloth 8 such as wool or serge. These two materials are then permanently and intricately united together all over their contacting surfaces by the use of rubber cement 9, and are in this way made into practically 75 a single fabric, having the double advantage of great strength and of neat appearance on 80 its outer side.

Laid across the outer or front side of the main portion or body of the vest are a plurality of strips of similarly formed material 10, 11 and 12. Of these strips, the lower- 85 most one 10 is cut to conform to the bottom of the vest and is securely sewed thereto. It is also sewed along the seams 13, 14 and 15 to produce three pockets 16, 17 and 18 as indicated in Fig. 1. The other two strips 11 90 and 12 are partially overlapping, the strip 12 being laid next to the body part and the strip 11 overlying the strip 12. They are then sewed together to the main part of the vest, to produce the pockets 19, 20, 21, 22 and 95 19', 20', 21' and 22'. There are thus two sets of pockets formed by these overlapping strips, of which the pockets 19', etc., are somewhat deeper than the others. The strips 10, 11 and 12 are so disposed on the body 100 part of the vest that a narrow transverse space is left between them and centrally in these spaces I provide two eyelets 23 and 24 for receiving the fastening means of a coin-handling device or the like, which is often 105 used by conductors for convenience.

The V-neck 25 of the garment is subject to heavy strain at times, and I have provided a simple and convenient reinforcing means therefor, shown in Fig. 2. It consists of a 110

V-shaped strip 26 conforming to the shape of the neck opening and applied to the edge of the same. A strip 27 is left on the edge of the fabric about this opening and is 5 turned in to cover the upper part of the V- strip 26, while the strip serves to protect and strengthen the edge of the opening.

The advantages of my improved vestlette are its strength and the numerous pockets 10 which are thus provided and which are so arranged as to allow for the attachment thereto of a coin-handling device.

Other modes of applying the principle of my invention may be employed instead of 15 the one explained, change being made as regards the mechanism herein disclosed, provided the means stated by the following 20 claim or the equivalent of such stated means be employed.

I therefore particularly point out and distinctly claim as my invention:—

In a garment of the character described, the combination of a main body part of flexible material, providing a V-shaped neck

opening at its upper edge, a reinforcing strip 25 of heavy material conforming to the shape of the neck opening and partially enclosed within the material at the edge thereof, a plurality of overlapping strips attached at their side and lower edges to the face of the 30 main body below the neck opening and extending transversely across said body, another transversely extending strip similarly attached, positioned adjacent the lower edge 35 of the main body and having an upwardly curved upper edge spaced from the adjacent straight edge of said overlapping strips, two parallel rows of stitching connecting all of said transversely extending strips to said main body and subdividing the same into 40 side and central compartments and eyelets secured to said main body adjacent said stitching in the space between said transverse strips, for receiving the fastening means of a coin-handling device. 45

Signed by me, this 28th day of July, 1919.

SAMUEL M. BLOCH.
